UNITED STATES PATENT OFFICE.

FRANK J. VIERLING, OF MINNEAPOLIS, MINNESOTA.

PENCIL.

1,317,743.

Specification of Letters Patent.

Patented Oct. 7, 1919.

Application filed March 6, 1919. Serial No. 280,992.

To all whom it may concern:

Be it known that I, FRANK J. VIERLING, a citizen of the United States, residing at Minneapolis, in the county of Hennepin and State of Minnesota, have invented certain new and useful Improvements in Pencils; and I do hereby declare the following to be a full, clear, and exact description of the invention, such as will enable others skilled in the art to which it appertains to make and use the same.

My invention has for its object to provide an improved pencil; and, to this end, it consists of the novel devices and combinations of devices hereinafter described and defined in the claims.

In the accompanying drawings, which illustrate the invention, like characters indicate like parts throughout the several views.

Referring to the drawings:—

Figure 1 is a view in elevation of the improved pencil;

Fig. 2 is a view partly in a longitudinal section taken centrally through one form of the improved pencil and partly in elevation, on an enlarged scale;

Fig. 3 is a view in transverse section taken on the line 3—3 of Fig. 2;

Fig. 4 is a detail view in transverse section taken on the line 4—4 of Fig. 2;

Fig. 5 is a fragmentary view partly in longitudinal central section and partly in elevation illustrating another method of securing the lead to the feeding device;

Fig. 6 is a view in elevation of the lead securing device shown in Fig. 5 removed from the pencil;

Fig. 7 is a view corresponding to Fig. 2, but illustrating another form of the improved pencil.

The numeral 8 indicates a tubular outer casing having a contracted lower end, or point 9. A guide block 10 and a sleeve 12 are pressed into the casing 8 and rigidly held, the former, at substantially the longitudinal center of said casing, and the latter at the top thereof. The guide block 10 has an irregular axial opening 11 with curved ends and parallel flat sides and the sleeve 12 has internal screw threads. Owing to the required diameter of the sleeve 12, it is necessary to circumferentially expand the casing 8 to receive the same.

55 A casing extension 13, of the same diameter as the expanded upper end of the

casing 8, is provided with a reduced lower end having external screw threads adapting the same to be screwed into the sleeve 12 to detachably connect said extension to the casing 8. The lower or inner end of the casing extension 13 also affords a shoulder 14, for a purpose that will presently appear.

Mounted in the casing 8 is a long feed-sleeve 15, which rests on the guide block 10 and is of such length as to project through the upper end of the casing extension 13. That portion of the sleeve 15 within the casing extension and projecting thereabove is circumferentially reduced to afford a shoulder 16 underlying the shoulder 14. Obviously the guide block 10 and shoulder 14 hold the sleeve 15 against endwise movement but with freedom for turning movement within the casing 8. Within the sleeve 15 is a feed-head 17 having, preferably, left hand screw threaded engagement with coarse internal screw threads 18 in the sleeve 13 and which screw threads extend from the lower end of said sleeve to the shoulder 16 thereof. Rigidly secured to the feed-head 17 is a feed-stem 19, the upper section of which is of the same form in cross section as the opening 11 in the guide block 10 in which it works with freedom for endwise movement, but is held thereby against turning movement. The lower section of the feed-stem 19 is, as shown, round in cross section and formed in its lower end is a lead holding seat 20 in which is removably secured, a lead 21.

To rotate the sleeve 15 and thereby impart a traveling movement to the feed-head 17 therein, there is pressed onto the upwardly projecting end of said sleeve, a finger piece in the form of a cap 22. The end of the sleeve 15 which extends into the cap 22 is longitudinally split to permit the same to yield when said cap is forced thereon and thereby frictionally hold the same. By turning the cap 22 with respect to the casing 8, a like movement is imparted to the sleeve 15 to operate a long nut on the feed-head 17 and impart an endwise movement to the feed-stem 19 and lead 21, and which lead extends through the open end of the casing point 9.

A new lead is preferably attached to the feed-stem 19 by removing said stem from the casing 8 and inserting the lead into the seat 20 and then replacing the feed-stem. To remove the feed-stem 19 from the casing

8. the cap 22 is first removed from the sleeve 15 and then the casing extension 13 is unscrewed from said casing. With the cap 22 and casing extension 13 removed the sleeve 15 may be lifted from the casing 8 which carries with it the feed-head 17, feed-stem 19 and attached lead 21. Extra leads may be kept in the upper end of the casing 15 and in which case they will be supported on the feed-head 17 and move therewith.

Referring now to the construction illustrated in Figs. 5 and 6 which shows a different method of attaching a lead to the feed-stem whereby substantially all of the lead may be fed through the opening in the casing point 9 to avoid waste. This lead holding member 23 has a tapered lower end or point which permits the same to be fed into the extreme lower end of the casing point 9. The lower end portion of the lead holding member 23 is provided with an axial bore affording a seat for a lead and it is also longitudinally split to yield and frictionally hold the lead. The lead holding member 23, above its lead seat, is recessed at 24 to receive the lower end portion of the feed-stem 19. Formed on the feed-stem 19, above the lower end thereof, but within the recess 24, is a shoulder 25. The upper end of the lead holding member 23 is closed by a plug 26 having an axial opening for the feed-stem 19, and which plug affords a stop for the shoulder 25 and thereby connects the lead holding member 23 to the said stem 19 with freedom for limited endwise movement. Normally, the lead holding member 23 is suspended from the shoulder 25 on the feed-stem 19 with the upper end of the lead 21 in engagement with the lower end of said feed-stem and which feed-stem provides a positive feed for the lead. Under the feeding action of the feed-stem 19, produced by turning the cap 22 to the right, the lead holding member 23 is caused to travel toward the lower end of the casing point 9. When the lead holding member 23 comes in contact with the side walls of the casing point 9, said walls become a fixed base of resistance for said member. Under further endwise movement of the feed-stem 19, the lead 21 will be moved endwise from the lead holding member 23, thus making it possible to use substantially all of the lead. It will be noted that the sides of the lead holding member 23 are flattened so as to permit the same to be inserted through the guide block 10.

Referring to the construction shown in Fig. 7, it will be noted that in place of the guide block 10, a feed-nut 27 is rigidly secured to the casing 8 and in which nut is mounted a feed-screw 28. The feed-stem 19 in this construction is round in cross section throughout its entire length. Integrally formed with the upper end of the feed-screw 28 is a guide stem 29 of the same form, in

cross section, as the upper portion of the feed-stem 19 in Fig. 2. This guide-stem 29 is mounted in a guide block 30, with freedom for endwise movement but is held thereby against turning movement. The guide block 70 30 is pressed into the central portion of the sleeve 15 and securely held in a fixed position. On the upper end of the guide-stem 29 is a stop plug 31 arranged to engage the guide block 30, when the sleeve 15 is removed from the casing 8, and thereby carry with it, the feed screw 28 and parts carried thereby. Extra leads may be carried in the upper end of the sleeve 15 and supported on the guide block 30. In actual construction 80 the screw 28 may be located lower in the casing 8 so that the guide stem 29 will be entirely out of the contracted upper end of the sleeve 15.

What I claim is:—

85

1. A pencil comprising a casing having a fixed guide block, a casing extension detachably secured to said casing, a lead feeding member rotatively mounted in the casing and its extension, said member being held against endwise movement by the casing extension and the guide block, a lead feeding stem working through the guide block with freedom for endwise movement but held thereby against turning movement, 95 and means including screw-threads for imparting endwise movement to said stem under the rotary movement of said member.

2. A pencil comprising a casing having a fixed guide block, a casing extension having screw-threaded engagement with the casing, a lead feeding member rotatively mounted in the casing and its extension, said member being held against endwise movement by the casing extension and guide block, a lead 100 feeding stem working through the guide block with freedom for endwise movement but held thereby against turning movement, and means including screw-threads for imparting endwise movement to said stem 105 under the rotary movement of said member.

3. A pencil comprising a casing having a fixed guide block, a casing extension having screw-threaded engagement with the casing, a sleeve rotatively mounted in the casing and 115 its extension, said sleeve being held against endwise movement by the casing extension and guide block, a head mounted in the sleeve and having screw-threaded engagement therewith, a lead holding stem secured to the head and working through the guide block with freedom for endwise movement but held thereby against turning movement, and a cap for the casing extension and having detachably frictional engagement with 125 the sleeve for turning the same.

4. A pencil comprising a casing having a fixed guide block, a lead feeding member rotatively mounted in the casing, means including said guide block for holding the lead 130

feeding member against endwise movement, and a lead feeding stem having screw-threaded engagement with the lead feeding member and working in said guide block 5 with freedom for endwise movement but held thereby against rotation.

5. A pencil comprising a casing having a fixed guide block, a tubular lead feeding member rotatively mounted in the casing, 10 means including said guide block for holding the lead feeding member against endwise movement, and a lead feeding stem

working in the guide block with freedom for endwise movement but held thereby against rotation and provided at its upper end with 15 a head extending into the lead feeding member and having screw-threaded engagement therewith, said lead feeding stem also having on its lower end lead holding means.

In testimony whereof I affix my signature 20
in presence of a witness.

FRANK J. VIERLING.

Witness:

HARRY D. KILGORE.
